UNITED STATES PATENT OFFICE

FRANK R. WHITE, OF DALLAS, TEXAS, ASSIGNOR OF ONE-HALF TO H. C. BAKER, OF DALLAS, TEXAS

SYSTEM OF ASSEMBLING AND LOCKING PRINTING PLATES

Application filed November 21, 1929. Serial No. 408,800.

This invention relates to new and useful improvements in systems of assembling and locking printing plates.

One object of the invention is to provide improved means for locking a metal printing plate upon a base in an easy and expeditious manner.

Another object of the invention is to combine a plate locking means with the usual column spacers so as to take the place of the usual slug or the line rule between columns.

A particular object of the invention is to provide a system of fastening printing plates and making up forms, whereby type may be combined with plates in an economical and secure manner and various sizes and shapes readily combined, thus making for flexibility.

A still further object of the invention is to provide locking means for holding plates on adjacent blocks and also for holding adjacent blocks against upward displacement.

A construction designed to carry out the invention will be hereinafter described together with other features of the invention.

The invention will be more readily understood from a reading of the following specification and by reference to the accompanying drawings in which an example of the invention is shown, and wherein:

Figure 1 is a fragmentary isometrical view, partly in elevation and partly in section, showing several blocks and plates assembled and locked together.

Figure 2 is an isometrical view of one of the blocks.

Figure 3 is an isometrical view of a block, plate and type assembly.

Figures 4 and 5 are details of locking lugs provided with ruling faces,

Figure 6 is an isometrical view of another block, type and plate combination,

Figure 7 is a fragmentary isometrical view, partly in section and partly in elevation, showing plate and block locking means,

Fig. 8 is a perspective of one of the locking lugs without a ruling face, and,

Figures 9 and 10 are sectional details of the same.

In the drawings the numeral 10 designates a block having a flat upper face 11 and which

may be of any suitable shape. This block may be made of wood, metal, or other suitable material, and has an angular groove 12 in its sides and ends. Upon the block is placed the printing plate 13, such as an electrotype half-tone or other etching. The plate and block are made of standard size so that when assembled the printing face of the plate will be "type high".

It is common practice to secure the plate 13 to the block by tacks and other temporary fastenings and this is objectionable because the block can only be used for one plate and considerable time is required to mount the plates and disconnect them from the blocks. In carrying out the invention I provide lugs 14 which may vary in shape and size. Each lug 14 is provided with a transverse rib 15 at such a height as to engage in the groove 12 of the block 10, thus holding the lug against upward displacement.

The plate 13 is provided with bevelled edges 16 flush with the sides and ends of the block 10 and each lug 14 has an undercut or bevelled lip 17 at its upper end so as to overhang and rest upon the bevelled edge 16, as is shown in Figure 1. It will be seen that when the lugs are held in place they will securely fasten the plate on the block.

In Figure 1 several combinations are shown. For instance, at A the lug is made thick enough to space the elements apart and yet hold the plate in place, but is not type high; while at B two lugs 14 are employed and when placed back to back have the same thickness as the lug A, but serve to fasten adjacent plates and adjacent blocks. At C in Figure 1 the lug 14 is provided with a ruling face 18 which is type high, and the lug has the same thickness as at A.

Another combination is shown in Figure 1 at D where lugs with ruling faces 18 are placed back to back and staggered so that ordinary printing rules E may be placed between adjacent plates and aligned with the ends of the staggered lugs. At F the lug 14 is provided with a double ruling face 19, which is shown in detail in Figure 5. It is to be understood that where the lugs are not type high the gaps therebetween may be filled.

in with ordinary printing slugs and these have been omitted for the sake of clarity.

It will be apparent that this system permits the use of plates of all sizes and shapes, thus making for adjustability, flexibility and economy in assembling. The system not only applies to plates with continuous edges, but plates with irregular edges, mortises or recesses. The plate 13 may be cast with the bevelled edge 16 or a plate which has been previously cast may be provided with this bevelled edge.

In Figure 3 I have shown an assembly comprising a pair of triangular blocks 10', each having the grooves 12 on three sides. In this assembly the plates 13 are shaped to the contour of their respective blocks and type or a type slug 20 is set between the blocks. The style of lugs 14 are used which are employed at A in Figure 1, but of course any of the other styles of lugs may be used.

In Figure 6 a mortised block 110 is used and the plate takes the form of a cut out border 13' having bevelled edges 16' and held by suitable lugs 14. Within the block and border plate a small plate 113 is held in place by suitable lugs 14 on the block, not shown but constructed in accordance with those illustrated. This gives another illustration of what might be done with this system.

In some instances it may be desirable to fasten adjacent blocks against relative vertical displacement and means for doing this is illustrated in Figures 7, 9 and 10. In Figure 7 an irregular plate 13 is shown and A and C styles of lugs are employed. For uniting two blocks 10a and 10b, a key 21 is employed, as is shown in Figures 7 and 10. This key is rectangular with a notch so as to fit in the groove 12 of one block and engage in the corner of the groove of the other block. A T-shaped key 22, shown in Figures 7 and 9, may be used in some instances and when inserted in the grooves 12 of adjacent blocks will prevent relative vertical displacement.

Various changes in the size and shape of the different parts, as well as modifications and alterations, may be made within the scope of the appended claims.

50 What I claim, is:

1. The system of mounting printing plates which consists in providing a base block with longitudinal grooves in one or more of its upright exterior walls, and securing a printing plate upon said base block by means of exterior lugs having transverse projections engaging in the groove of the block and overhanging the plate on top of the block.

2. The system defined in claim 1, and including a printing rule formed on the upper end of the lugs.

3. In a printing system, a base block having longitudinal grooves in one or more of its upright exterior walls, a printing plate mounted on the top surface of the block and

having one or more bevelled edges contiguous to the grooved walls of the block, and one or more exterior upright lugs having transverse ribs engaging in the grooves of the block and also provided with overhanging lips engaging the bevelled edges of the plate.

4. The combination set forth in claim 3, with a printing rule integral with the upper end of one or more of the lugs.

5. The system of mounting printing plates which consists in providing adjacent blocks with longitudinal grooves in their adjacent upright walls, disposing printing plates on top of the blocks and inserting spacers between said blocks having projections extending into the adjacent grooves of said blocks and also having projections at their upper ends overhanging the adjacent edges of the plates, whereby said plates are spaced apart and are locked on their blocks.

6. The system defined in claim 5, with locking lugs detachably applied to the non-adjacent upright walls of the block for locking the plates thereon.

In testimony whereof I affix my signature.

FRANK R. WHITE.
